(57) **CLAIM**

The ornamental design for a package for feminine hygiene products, as shown and described.

DESCRIPTION

This application is a divisional of application Ser. No. 29/395, 198 now Design Pat. No. D695,609.

FIG. 1 is a front, top and right side perspective view of a package for feminine hygiene products, showing my new design; and,

FIG. 2 is a right, top and back side perspective view thereof, the left side is identical to the right side shown, but without the dash-dot line.

The even dash broken line represent unclaimed environment and forms no part of the claim design. The dash dot line represents the perforated line. The white and black lace surface areas represent a contrast in appearance.

1 Claim, 2 Drawing Sheets

FIG 1

FIG 2
